UNITED STATES PATENT OFFICE.

GOMERT POWELL, OF MICHIGAN CITY, INDIANA, ASSIGNOR TO PULLMAN CAR AND MANUFACTURING CORPORATION, A CORPORATION OF ILLINOIS.

METAL-BREAKING DEVICE.

Application filed August 15, 1924. Serial No. 732,335.

This invention relates to metal breaking devices and more particularly to devices for breaking railway car wheels preparatory to charging cupola furnaces with the same.

5 One of the objects of the invention is the provision of new and improved means for breaking into smaller pieces cast metal articles such as railway car wheels and the like in order that the smaller pieces may the 10 more easily be melted in the furnace within which they are deposited together with new and improved means for preventing injury to persons and property by flying particles of the broken material during the breaking 15 operation.

Another object of the invention is the provision of a new and improved shield or mantle mechanism for a wheel breaking device and means for automatically raising 20 and lowering the same during the breaking operation.

Further objects of the invention will appear in the following description taken in connection with the accompanying drawings, 25 in which

Fig. 1 is a side elevation of the device;

Fig. 2 is an elevation at right angles from that shown in Fig. 1, with parts in section;

Fig. 3 is an elevational view of a detail, 30 with parts in section;

Fig. 4 is a sectional plan view on line 4—4 of Fig. 1;

Fig. 5 is a vertical section of the guide and anvil showing the weight and shroud or shield in lowered position;

Fig. 6 is a similar view showing the weight and shroud or shield in partially elevated position;

Fig. 7 is a plan view of the charging 40 motor, with parts in section; and

Fig. 8 is a section on line 8—8 of Fig. 7.

While the device is adapted to break into smaller pieces metallic articles of various kinds, it is especially adapted to break discarded car wheels and the like into smaller particles in order to facilitate the melting of the same. For simplicity of illustration and convenience of description a car wheel breaking device has been selected to disclose one 50 embodiment of the invention.

On the drawing, the reference character 10 designates an anvil on which the car wheel or other metallic article 11 is adapted to be placed preparatory to breaking the same.

The anvil 10 is supported in any convenient 55 manner, as by means of the base 12.

The wheel is adapted to be broken by a falling weight 13 which is elevated and released as in pile driving machinery. As shown, a suitable tower comprising the uprights 14 and bracing members 15 is mounted over the anvil and forms a support for the vertically extending guides or leaders 16 and 17 which may be in the form of I-beams spaced apart as shown in Fig. 4, and which 60 constitute a guideway for the hammer or weight 13. The guides 16 and 17 are connected together by the members 18 and are braced from the tower by suitable braces 19 and 20. In order that the hammer or weight 65 70 may be readily removed for replacement or repairs or for removing small particles of the broken metal that may be projected upwardly and become wedged between the guides and the hammer or weight, one of the 75 guides or leaders as 16 is pivoted at its upper end as at 21, whereby the same may be swung outwardly and the piece of broken metal, or the weight, removed when desired.

Suitable means are provided for raising 80 the weight or hammer 13 and for automatically releasing the same when it reaches a predetermined height. As shown, the weight is reduced at its upper end to form a head 22 having oppositely arranged shoulders 23 thereon. The shoulders may be formed by steel inserts as shown in Fig. 5. The shoulders 23 are adapted to be detachably engaged by a pair of weight engaging members or tongs 24 pivoted to the tong 85 housing 25 slidably mounted in the guideway formed by the leaders 16 and 17. The housing 25 is raised by means of a cable 26 which is connected to said housing and is trained over suitable sheaves or pulleys 27 90 on the top of the tower under a pulley 28 at the base of the tower and over a pulley 31 mounted on the piston 32 of the hydraulic lifting motor 33. The lower end of the cable 26 is secured by any suitable means at 95 the base of the motor 33. The motor 33 is controlled by a valve operating lever 30 in the usual or any well known manner, the water entering through the pipe 380 and being discharged through the pipe 39 as is 100 105 usual in such constructions.

The tongs 24 are so constructed that when the housing 25 is lowered they will auto-

matically engage the shoulders 23 as is usual in such constructions. The tongs are provided with the extensions 35 bent to form inclined surfaces for engaging release blocks 36 and 37 at the upper end of the guideway for automatically releasing the weight 13 and permitting the same to fall by gravity on to the anvil 10 for breaking metallic articles placed thereon.

10 In breaking metallic articles in this manner, broken particles are likely to be projected in all directions, and in order to prevent injury to persons or property, means are provided for surrounding the article on 15 the anvil during the descent of the weight.

In the form of the device selected to illustrate one embodiment of the invention, a shroud or shield 38 is employed for this purpose. The shroud is provided at its lower 20 end with an enlarged recess 39 which is adapted to extend over and about articles placed on the anvil, and its upper end is provided with a guide 41 which is adapted to conform to the contour of the outer 25 surface of the guideway formed by the leaders 16 and 17, as clearly shown in Fig. 4 of the drawing. The shroud is adapted to engage the anvil 10 and form a housing or shield for the wheel 11 or other metallic article 30 during the breaking operation.

Suitable means are provided for automatically elevating the shield for permitting removal of the broken article and the insertion of a new one. Any suitable means may be 35 employed for this purpose. As shown, the guides 41 of the shield are provided at opposite sides thereof with dogs or latches 42 and 43 which are adapted to engage shoulders 44 and 45 secured to the weight 13. The 40 latches 42 and 43 are provided with weights 46 which are adapted to hold the said latches in retracted position. Suitable stops 46^a limit the downward movement of the weights 46. A lever 47 is provided at each 45 side of the leaders for engaging the latches 42 and 43. These levers are pivoted to brackets 48 extending in opposite direction from the said leaders. Each lever is provided with an arm 49 for engaging the corresponding latch and with an upwardly extending arm 51 for engaging cam surface 52 provided on each side of the tong housing 25. The arms 51 may be provided with suitable anti-friction rollers for engaging said cams. In the operation of the device, the shield is lowered in position over the article to be broken and the weight is released, which will break the article into fragments. The tong block 25 is now lowered, and the tongs will automatically engage the shoulders 23 for raising the weight. In the meantime the arms 51 will engage the cam surfaces 52 as the block 25 descends thereby moving the latches 42 and 43 inwardly to engage the shoulders 44 and 45.

The tong block 25 is now elevated, carrying with it the weight 13 and the shield or shroud 38. The shield or shroud 38 continues to be elevated until the inclined surfaces 53 of the latches 42 and 43 engage the 70 cams 54 secured to the runners 16 and 17. Before the latch members come in contact with the cams 54 the cam surfaces 52 will have passed upwardly beyond the arms 51, thereby permitting the latches 42 and 43 to 75 move outwardly when they engage the cams 54, to thereby release the shield and to permit the same to drop back on the anvil 10.

Suitable means are provided for recharging or for moving metallic articles on to the 80 anvil and for removing the same after they have been broken. Any suitable means may be employed for this purpose. As shown, a hydraulic motor 55 is employed. The motor may be of the usual or any well-known construction and comprises the stationary piston 60 and the movable cylinder 57 to which is attached the plunger 58, operating in the guideway 59. The cylinder 57 is retracted by means of a weight 61 connected thereto 90 by a cable 62 extending over a pulley 63. The weight 61 is adapted to be raised and lowered in the well 64 provided for that purpose. The motor 55 is controlled by the operator by means of the lever 56 (see Fig. 95 4), in the usual manner. Where the device is employed for breaking car wheels as in the form of the apparatus illustrated, the front end of the plunger 58 is curved as at 100 61 to conform to the curvature of the wheel.

In the operation of the device, after a wheel has been broken by the descent of the weight 13 and the wheel has been placed in the guide 59 in front of the plunger 58, the operator moves the valve 33^a to raise the 105 weight and shroud above the wheel and anvil. The upward movement of these members is stopped when the same is above the wheel 11 and the valve lever 56 is operated to cause the plunger 58 to advance, moving the 110 wheel 64 on to the anvil and forcing the broken wheel off of the same. After the plunger 58 has returned, the block 25 is again moved upwardly, which causes the 115 latches 53 to engage the cams 54 to release the shroud, which will thereby descend on the anvil over and about the wheel 11. The parts are now in position for the descent of the weight 13, which occurs when the extensions 35 engage the cams 36 and 37.

It is thought from the foregoing taken in connection with the accompanying drawings that the construction and operation of my device will be apparent to those skilled in the art. Various changes in size, shape, proportion and details of construction may be made without departing from the spirit and scope of the appended claims.

I claim as my invention:

1. In a metal breaking device, an anvil, a 130

shroud for engaging the upper surface of said anvil, said shroud being provided with a central opening and being adapted to extend over and about an article placed on said 5 anvil, means for dropping a weight onto said article through said opening and means for removing said shroud preparatory to removing said article from said anvil.

2. In a metal breaking device, a vertical 10 guideway comprising a stationary leader, a support therefor, a movable leader, means for pivotally connecting said movable leader to said support, and a weight slidably mounted in said guideway.

15 3. In a metal breaking device, a tower, a guide member fixedly secured in vertical position to said tower, a guide member hingedly connected to said tower, means for holding said members in spaced relation, and 20 a weight slidably mounted in the guideway formed by said guide members.

4. In combination, an anvil, a guideway 25 above said anvil, a weight having shoulders thereon slidably mounted in said guideway, means including a tong block for elevating said weight, and for automatically releasing

the same, a cam surface on said block, a shroud slidably mounted on said guideway, a latch on said shroud, means for normally holding said latch in released position, a 30 lever pivoted to said guideway and having one arm engaging said latch and having its other arm adapted to engage said cam surface when said block is at its lowermost position for moving said latch in the path of said shoulder for raising said shroud when said weight is elevated, and a release block 35 on said guideway for engaging said latch for releasing the same during the elevation of said weight.

40 5. In combination, an anvil, a guideway above said anvil, a weight slidably mounted in said guideway, means for raising said weight, shoulders on said weight, a shroud above said anvil, latches carried by said 45 shroud and adapted to engage said shoulders for elevating said shroud when said weight is raised, and means for automatically releasing said latches when said shroud has reached a predetermined height.

GOMERT POWELL.
